UNITED STATES PATENT OFFICE

130,526

DESIGN FOR A HOLDER FOR SMALL FILES AND OTHER TOOLS

Oscar L. Swenson, Toledo, Ohio, assignor of forty-nine per cent to Ben J. Cheeseman, Toledo, Ohio

Application September 10, 1941, Serial No. 103,264

Term of patent 14 years

To all whom it may concern:

Be it known that I, Oscar L. Swenson, a citizen of the United States and resident of Toledo, in the county of Lucas and State of Ohio, have invented a new, original, and ornamental Design for a Holder for Small Files and Other Tools, of which the following is a specification, reference being had to the accompanying drawing, forming a part thereof.

In the drawing, Fig. 1 is a perspective view of a holder for small files and other tools showing my new design; Fig. 2 is a side elevation, and Fig. 3 an end elevation thereof.

I claim:

The ornamental design for a holder for small files and other tools, substantially as shown.

OSCAR L. SWENSON.
